UNITED STATES PATENT OFFICE.

ISADOER BURTON, OF PITTSBURGH, PENNSYLVANIA.

MINING MACHINE.

Application filed February 26, 1925. Serial No. 11,825.

To all whom it may concern:

Be it known that I, ISADOER BURTON, a citizen of the United States, residing at Pittsburgh, in the county of Allegheny and

5 State of Pennsylvania, have invented certain new and useful Improvements in a Mining Machine, of which the following is a specification.

The present invention relates to a mining 10 machine, and has for its principal object to provide means for digging coal or mineral ore and delivering the same to a loading apparatus.

Another very important object of the 15 invention is to provide a mining machine of this nature wherein the digging apparatus may be extended at different angles from the carriage and wherein the loading apparatus may also be disposed at different angles to 20 the carriage and to the digging apparatus.

A still further very important object of the invention is to provide a mining machine of this nature which possesses a simple structure that is easy to adjust, one which is efficient and reliable in operation, strong, durable, and well adapted to the purpose for 25 which it is designed.

With the above and numerous other objects in view as will appear as the description 30 proceeds, the invention resides in certain novel features of construction, and in the combination and arrangement of parts as will be hereinafter more fully described and claimed.

35 In the drawing:—

Figure 1 is a top plan view of the machine embodying the features of my invention,

Figure 2 is a longitudinal vertical section therethrough,

40 Figure 3 is an enlarged detail section through one of the blocks on the conveying mechanism in the loader,

Figure 4 is an enlarged transverse section through the digging apparatus, and

45 Figure 5 is a vertical section taken substantially on the line 5—5 of Figure 2.

Referring to the drawing in detail, it will be seen that the carriage 5 is mounted on 50 wheels 6 which travel on suitable tracks 7.

55 A digging apparatus A extends forwardly of the carriage 5 and communicates at its upper end with a chute B. The bottom end of this chute B communicates with the loading apparatus C.

60 The chute B includes a frusto-conical upper portion 8 and a frusto-conical bottom

portion 9. The lower end of the portion 8 overlaps the inner surface of the portion 9. The portion 9 is provided with an interior flange 10 and brackets 11 depend from the 60 interior of the portion 8 and support rollers 12 which engage the under surface of the flange 10 for holding the upper portion 8 on the lower portion 9. The upper portion 8 is prevented from slipping down into the lower 65 portion by the beveled gear member 13 arranged annularly and exteriorly thereof, and meshing with a beveled gear 14 operable by a suitable prime mover such as the electric motor 15 carried by the carriage 5. The 70 lower portion 9 is supported on the carriage by members 16 and is provided with an exterior annular flange 17 for a purpose which will be described later.

The digging apparatus comprises a conveyor structure wherein a forwardly and downwardly slanting trough 17 has its upper end mounted on bracket 18 rising from the upper portion 8 of the chute B. This trough 17 is provided with suitable upstanding sides 19. Chains 20 are trained through the trough and over sprockets 21 on shafts 22 and 23, the latter being at the upper end of the trough and driven by a suitable prime mover such as the electric motor 24 carried by a bracket 25 supported on the upper portion 8 of the chute. A plurality of transversely curved shovel blades 26 are mounted across the chains 20 and travel over the bottom of the trough 17 and are adapted to 85 pick up the coal and cause the same to travel up the chute 17 and to be dumped into the chute B. By energization of the motor 15 it will be seen that the upper portion A of the chute may be rotated for placing the 90 digging apparatus at different angles in relation to the carriage.

The loading apparatus C embodies a conveyor structure wherein a trough 30 has an intermediate slanting portion terminating in a horizontal portion at its lower end, and at its upper end in a horizontal portion which may be disposed over a wagon or the like for dumping the coal or the like therein. This trough 30 is provided with sides 31 which rise therefrom. On the lower and upper horizontal portions these sides are continued downwardly as at 32 and 33. The forward portions of the sides 33 are connected by a horizontal bottom 34 which merges into 100 a rearwardly disposed downwardly slanting bottom 35. The sides 32 are connected 105

with a horizontal bottom 36. Shafts 37 and 38 are journaled in the sides 31, and have mounted thereon sprockets 40 over which is trained the chain 41 which supports a plurality of transversely extending blocks 42 for moving them along the bottom of the trough 30. The shaft 39 is driven by a suitable motor or other prime mover 44 mounted on a bracket 45 extending from one side 10 31. It is preferable to construct these blocks 42 of wood and to cover them with sheet metal as at 46. The upper end of the loading apparatus is supported by providing the bottom portion 34 with a detent 47 rideable in 15 a groove provided in an arcuate rail 48 supported by the screw jack structure 49 on the carriage 5. The lower end of the loading apparatus is supported by providing the sides C with overhanging extensions 57 engageable on the annular flange 17' provided on the exterior of the lower portion 9 of the chute B. It will thus be seen that the rear 20 end of the loading apparatus may be swung laterally of the carriage at different angles 25 thereto and at different angles to the digging apparatus.

It is thought that the construction, operation, and advantages of the invention will now be clearly understood without a more 30 detailed description thereof. It is desired, however, to point out that numerous

changes in the details of construction, and in the combination and arrangement of parts may be resorted to without departing from the spirit or scope of the invention as hereinafter claimed or sacrificing any of its advantages. 35

Having thus described the invention, what I claim as new is:—

1. In a mining machine of the class described, a carriage, a chute mounted on the carriage including an upper rotatable portion and a lower stationary portion, means for turning the upper rotatable portion of the chute, a digging and conveying apparatus mounted on the rotatable portion of the chute, and a loading conveying mechanism rotatably mounted on the stationary portion of the chute therebelow. 40 45

2. In a mining machine of the class described, a supporting structure, a chute including a lower stationary portion, and an upper rotatable portion, means for holding the two portions of the chute together, means for rotating the upper portion, a combined digging and conveying apparatus mounted on the upper portion, and a combined loader and conveyor mounted for rotation on the lower portion and extending upwardly and rearwardly therefrom. 50 55 60

In testimony whereof I affix my signature.
ISADORE BURTON.
